(57) **CLAIM**

The ornamental design for a interbody spinal implant, as shown and described.

DESCRIPTION

FIG. 1 is a perspective view of an interbody spinal implant in accordance with the invention;

FIG. 2 is a front elevational view of the implant;

FIG. 3 is a first side elevational view of the implant with the

second side elevational view being a mirror image thereof;

FIG. 4 is a rear elevational view of the implant; and,

FIG. 5 is a top plan view of the implant with the bottom plan view being a mirror image thereof.
